INVENTOR:

Louis J. Monahan

UNITED STATES PATENT OFFICE.

LOUIS J. MONAHAN, OF OSHKOSH, WISCONSIN.

DESIGN FOR A GAS-ENGINE FRAME.

42,696.

Specification for Design.

Patented July 2, 1912.

Application filed March 4, 1912. Serial No. 681,669. Term of patent 3½ years.

To all whom it may concern:

Be it known that I, LOUIS J. MONAHAN, a citizen of the United States, residing at Oshkosh, in the county of Winnebago and State of Wisconsin, have invented a new, original, and ornamental Design for a Gas-Engine Frame, of which the following is a specification, reference being had to the accompanying drawing, forming part thereof.

The figure is a perspective view of a gas

engine frame with bearings, lugs, cylinder and water tank integral, showing my new design.

I claim.

The ornamental design for a gas engine frame as shown and described.

LOUIS J. MONAHAN.
